UNITED STATES PATENT OFFICE.

JOHN QUEEN SLYE, OF WASHINGTON, DISTRICT OF COLUMBIA, ASSIGNOR TO STAND-
ARD APPLIANCE AND SOUVENIR COMPANY, OF WASHINGTON, DISTRICT OF CO-
LUMBIA, A CORPORATION OF THE DISTRICT OF COLUMBIA.

FIBER-NEEDLE SHARPENER FOR TALKING-MACHINE RECORDS.

Application filed June 3, 1922. Serial No. 565,758.

To all whom it may concern:

Be it known that JOHN QUEEN SLYE, a citizen of the United States of America, residing at Washington, in the District of Columbia, has invented new and useful Fiber-Needle Sharpeners for Talking-Machine Records, of which the following is a specification.

As a rule wooden needles are used principally in connection with the best records, namely those which are rendered by the best singers and players, for instance, such as operatic music and the best songs in general.

A great many needles of this character are used and it is also known that when a fiber needle has been once used it is discarded. Possibly a needle may be used twice. And due to the fact that such needles are discarded after having been used once or twice, a great many needles are used.

Heretofore, as disclosed in the co-pending application of John Queen Slye filed on the 27th day of May, 1922, Serial No. 564,161, a suitable sharpening device has been employed to sharpen fiber needles. The device as embodied in said application is supported detachably from the table of the talking machine. There are objections more or less to this character of sharpening device, due to the attachable and detachable connections between it and the table. The ring in this application and which constitutes the sharpener is mounted concentric with the table and has means to switch the needle from the sharpening track or groove on the ring to the record which may be supported upon the table.

The present device has for its purpose the provision of a sharpener, either forming an integral part of the record, or separable therefrom and has an eccentrically disposed track connecting the sharpening track and the sound wave or groove of the record, so that as the fiber needle tracks around the sharpening groove or track it will automatically transfer or switch from the sharpening track to the sound groove.

Another purpose is to provide a sharpener of this character capable of being subsequently applied to all records, or, as previously stated, being made an integral part of the records to be molded.

It is to be understood that the particulars herein given are in no way limitative and

while still keeping within the scope of the invention, any desired modification of detail and desired proportions may be made in the apparatus according to circumstances.

The invention comprises further features and combinations of parts as will be herein-after set forth, shown in the drawings and claimed.

In the drawings:

Fig. 1 is a plan view of a talking machine record, showing the face of the record as provided with a sharpening track or groove adjacent the marginal edge of the record and connecting with the sound groove of the record.

Fig. 2 is a sectional view through the record on line 2-2 of Fig. 1, also showing a blank sheet of some suitable material to cover the sound groove while emery is being applied to the sharpening track.

Fig. 3 is an enlarged detail sectional view of a portion of a record, showing the sharpening track.

Fig. 4 is still another enlarged view of a portion of a record, showing a ring provided with a sharpening track and connected to the marginal edge of a record.

Fig. 5 is a plan view of a record, showing a ring applied to the marginal edge thereof, said ring having a spiral sharpening track.

Fig. 6 is a sectional view on line 6-6 of Fig. 5.

Fig. 7 is an enlarged sectional view of a portion of the record shown in Fig. 6 showing the ring with its sharpening track on an enlarged scale as applied.

Referring to the drawings, 1 designates a conventional form of talking machine record which is provided with the usual sound wave groove 2. This record is designed to be made of the usual material from which records are made, and during the course of construction the face of the record, near its marginal edge 3, is supplied with a spiral sharpening groove 4, considerably deeper than the sound wave groove. In fact the sharpening groove or track 4 in actual practice is designed to be as deep as the beveled end 5 of a fiber needle 6 shown clearly in Fig. 3. The beveled end of such a needle is approximately $\frac{1}{16}$ of an inch, more or less, and by cutting down the surface of

the bevel 5, the needle will become sharpened. Fiber needles are as a rule triangular in cross section, and by providing a bevel on one end, one corner of the needle is formed 5 with the sharpening point which rides in the sound wave groove of the record.

The sharpening track or groove, approximately at a point indicated by the character 7, is connected by an eccentrically arranged track 8 with the sound wave groove at a point indicated by the character 9. Obviously, after once playing a record, and it is desired to repeat the record without changing the needle, the tone arm of a talking machine, not shown, may be shifted to the outer portion of the record so that the beveled face 5 of the fiber needle may engage the sharpening track 4. The sharpening track is approximately V-shaped in 20 cross section and it will be noted, as shown in Figs. 3 and 4, one wall 10 of the track 4 is relatively steep, while the opposite wall slopes on an angle approximately 45°. This latter more or less gradual sloping wall 11 when formed is roughened, in order that a very fine layer of emery or carborundum or similar finely granulated material may be applied thereon, as indicated at 12. After 25 roughening the gradual sloping face 11, it is first supplied with a fine coating of adhesive material thinly distributed. Prior to applying this thin coat of adhesive material, the face of the record, which is provided with the sound wave groove, is first covered 30 with a thin blank of suitable material, either paper, fabric or the like, such as indicated at 13 in Fig. 2. A suitable weight may be applied upon the blank to hold it flat against the face of the record, while the sharpening 35 track or groove is being supplied with the adhesive material or the emery or carborundum.

As previously stated the thin layer of adhesive is applied while the sound wave groove is covered and subsequently to this the emery or carborundum, in the finely granulated or powdered form, is sprinkled or blown into the groove. After the adhesive has partly dried, the surplus emery 45 or carborundum is blown or wiped from the margin of the record.

This action may be repeated two or three times before the adhesive becomes thoroughly dried and then after the adhesive is completely dry, a tool provided with suitable felt may be drawn through the track to insure wiping away the surplus emery or carborundum from the relatively steep wall of the groove and at the same time remove particles of the emery or carborundum from the sharpening side of the groove, namely the gradual sloping side of the groove. The emery or carborundum on the gradual sloping side of the groove may be further cut 50 down by a tool having a relatively hard

point. This hard-pointed tool is used subsequently to the use of the felt covered pointed tool.

In Fig. 5 the talking machine record is the same as that shown in Fig. 1, but instead of the sharpening track being formed in a part of the record, it is formed on a ring 14, which is subsequently applied to the record. In fact the ring fits the marginal edge of the record. It is well known that the marginal edges of all records are slightly rounded, therefore, in order to hold the ring 14 on the record, its inner marginal edge is undercut, as indicated at 15 in Figs. 6 and 7, more clearly shown in Fig. 7. Due to undercutting the inner edge of the ring, the ring is caused to be formed with an overhanging marginal lip 16, which overlies the upper portion of the rounded edge of the record, thereby acting to support the ring on the record, while the record may be supported upon the table.

The sharpening track in the ring 14 is formed in the same manner as the sharpening track carried by the record in Fig. 1. As shown in Fig. 5, the sharpening track, from a point indicated at 18, merges into an eccentric portion 19, which terminates adjacent the inner edge of the ring. The sound wave groove 20 on the record, in Fig. 5, has an eccentric extension 21, which is designed to gradually increase in size toward the marginal edge of the record to a point as indicated at 22 where it may join the eccentric extension 19 of the sharpening track of the ring. Obviously, when repeating the record shown in Fig. 5, the fiber needle is placed in engagement with the beginning of the sharpening track, and when it reaches the point or location 18, the needle automatically travels to the eccentric extension 19 (which merges into the eccentric extension 21), and then travels to the eccentric extension 21. As previously stated this latter extension gradually increases in size, that is to say, in cross section to a point where it merges into the eccentric extension 19, therefore when the fiber needle travels to the extension 21, it gradually merges into the sound wave groove 20.

In Fig. 4 a needle sharpening ring is shown as applied to the marginal edge of a record 23. This record is provided with a sharpening track similar to those illustrated in the other figures, but this ring 24 is applied to the record subsequently to the construction of the record. This is accomplished by providing registering recesses 25 and 26 in the adjacent edge portions of the record and the ring, in which suitable metal plates or fasteners 27 may be embedded to hold the ring and the record rigidly connected, so as to rotate with the record as one body. These fasteners or plates are to be located so that the eccentric extensions 19

and 21 will register when the ring is applied to the record.

A sharpening track or groove of this character will remove or shave down just sufficient of the beveled end of a fiber needle, to sharpen the point or corner of the needle, sufficiently to properly track in the sound wave groove of the record, in order to reproduce the record in the same manner as 10 if reproduced by an entirely new needle.

What is claimed is:

1. A talking machine record provided with a needle sharpening spiral track and an eccentric continuation of said track leading 15 into and connecting with the record groove.

2. A talking machine record provided with a needle sharpening spiral track connected with the sound wave groove of the record, whereby the needle to be sharpened 20 may automatically transfer from the sharpening track to the sound wave groove.

3. A talking machine record including a sound wave groove and provided with a spiral needle sharpening track adjacent the 25 marginal edge of the record, and an eccentric connecting track connecting the spiral sharpening track and the sound wave groove, whereby the needle to be sharpened automatically transfers from the sharpening 30 track to the sound wave groove.

4. A talking machine record having a sound wave groove, the upper face of the record adjacent its marginal edge provided 35 with a spiral sharpening track of a length sufficient to impart a sharpening action to the stylus as the record makes at least one complete revolution, an eccentric groove tapering from the sharpening track to the sound wave groove and thereby connecting 40 the sharpening track and the sound wave groove, whereby a needle may automatically transfer from one to the other.

5. A talking machine record having a sound wave groove, a ring separably mounted 45 on the margin of the record and provided with a needle sharpening track, a needle transfer groove connecting the needle sharpening track and the sound wave groove of the record, to permit the needle to automatically transfer from one to the other.

6. A talking machine record provided 55 with a sound wave groove, of a ring carried by the marginal edge of the record and provided upon its upper surface with a needle sharpening track, an eccentric track connecting the sharpening track and the sound wave groove whereby the needle may automatically transfer from one to the other.

7. A talking machine record provided 60 with a sound wave groove, a ring provided with an under-cut inner edge and provided with an overhanging lip to overlie the edge

of the record and support the ring in position, said ring having a needle sharpening track, an eccentric groove connecting the 65 needle sharpening track and the sound wave groove, whereby a needle may automatically transfer from one to the other.

8. A method of constructing a sharpening track on a talking machine record, which first consists in cutting an eccentric track 70 on the upper face of the record near the marginal edge thereof, covering the sound wave groove, thereby exposing the surface having the sharpening track, applying an adhesive in said track, blowing or otherwise applying finely powdered emery or carborundum on the adhesive covered wall of the track, cutting down the emery covered 75 wall, then subsequently cleaning off the surface plus emery or carborundum.

9. A talking machine record provided with a sound wave groove, the upper face of the record between its marginal edge and the outer convolution of the sound wave groove having a sharpening track extending spirally from a point immediately adjacent the marginal edge of the record to the sound wave groove, whereby as a needle is sharpened, the record may travel at least a complete revolution, said spirally constructed 80 sharpening track having an abrupt spiral portion connecting with the sound wave groove.

10. The combination with a talking machine record provided with a marginal beveled edge extending slightly downwardly and outwardly, of a ring with its inner edge under-beveled to correspond to and engage 85 with the beveled margin of the record for separably supporting the ring on the record, said ring having a grinding track for sharpening a needle, said sharpening track having a transfer groove abruptly spiral and connecting with the sharpening groove and the sound wave groove to permit the needle to automatically transfer from one to the other.

11. A method of constructing the sharpening track of a talking machine record, which first consists in cutting a track on the upper face of the record between the sound wave groove and the margin of the record, spirally toward and connecting to the sound wave groove, covering the sound wave groove to expose the surface having the sharpening track, adhesively applying finely powdered emery or carborundum in the track and cutting down the emery covered 110 walls of the track, and subsequently cleaning off the surplus emery or carborundum.

In witness whereof, the inventor's signature is hereunto affixed.

JOHN QUEEN SLYE,
